UNITED STATES PATENT OFFICE.

JOHN FLAHERTY, OF CHICAGO, ILLINOIS.

FURNACE.

SPECIFICATION forming part of Letters Patent No. 635,469, dated October 24, 1899.

Application filed September 1, 1898. Serial No. 690,015. (No model.)

To all whom it may concern:

Be it known that I, JOHN FLAHERTY, a citizen of the United States, residing at Chicago, in the county of Cook and State of Illinois, 5 have invented a new and useful Improvement in Furnaces, of which the following is a specification.

My invention is in the nature of improved means for feeding coal-dust or other fuel in a 10 finely-divided state into a furnace designed for its consumption; and my object is to provide a construction of feeding means whereby a steady and even feeding may be effected under conditions insuring practically perfect 15 combustion.

In the accompanying drawings, Figure 1 is a view in perspective (certain parts being shown broken) of a furnace equipped with my improved firing means. Fig. 2 is a broken plan 20 section taken at line 2 of Fig. 1 and showing the angle at which the fuel-streams enter the combustion-chamber, and Fig. 3 a broken transverse vertical section showing a detail of construction of the fuel-box.

25 A represents the combustion-chamber of the furnace; B, the chimney-stack; C, the breech of the chimney, in this case utilized as an air-heating chamber; D, a fuel-box; E, a fuel and air pipe leading from a blower F 30 and communicating with the combustion-chamber through two branch pipes E' E², and E³ an intake-pipe for the blower, communicating through a branch pipe J with the fuel-box and through an extension E⁴ with an air- 35 heating coil E⁵, preferably located within the chimney-breech and provided exterior to the same with an air-inlet s.

The fuel-box D is provided with outwardly and downwardly sloping sides and with an inverted trough G, of V-shaped cross-section, 40 set into the bottom and forming with the sloping sides of the box and the horizontal bottom sections longitudinal channels H H', within which work worm conveyers I and I', 45 provided with driving-pulleys t.

Slidingly surmounting the ridge of the inverted trough G is a shaker, of saddle-board form, having a member G', provided with laterally-projecting fingers p, resting on each 50 slope of the ridge. The shaker is provided at one end with an operating-handle G². The purpose of the shaker is to loosen any dust

that may adhere to the sloping sides of the ridge after the coal has been lowered to the top of the ridge. For this purpose the device 55 may be worked back and forth by hand, or means for operating it automatically may be provided.

The pipe J joins the pipe E³ at such an angle as to permit its contents to be readily 60 drawn by suction into the latter, whence it is carried by the air-current through the fan, being thereby thoroughly shaken up and commingled with the air. From the fan the thoroughly-mixed air and fuel pass through the 65 pipe E into the branch pipes E' E², whence it issues in converging streams in substantially a horizontal plane into the front of the furnace, as shown in Fig. 2. The acute angle each tube forms with the furnace-front is 70 preferably in the neighborhood of forty-five degrees, or even less, so that the strong "pull" 75 present in ordinary constructions is avoided and the particles of carbon are consumed and the heat of combustion communicated to the boiler before the fine particles can be wafted beyond the combustion area or the combustion-gases can escape to dissipate their heat ineffectively.

The fan F and conveyer I are geared by 80 belts K and M to a drive-shaft L, supported in any suitable manner, and supplied with a pulley L', at which motion is imparted to the shaft. This particular arrangement of the gearing may be departed from; but it is quite 85 important that fan and conveyer be geared to a common motor or power source, so that both are affected correspondingly by a change in speed of the motor. The result thus attained is to affect the air and fuel supply correspondingly, 90 so that approximately the correct proportions are maintained.

The channel H' is supplied with a discharge-pipe N, which may communicate with the pipe E³ or with a similar fuel-duct leading to another furnace. Obviously where it is desired to use but one conveyer the second one may be left inoperative or the double channel may be dispensed with, one side of the V becoming a simple deflecting-board or inclined 95 bottom piece.

The operation is as follows: A quantity of coal-dust having been introduced into the box D from a suitable source of supply, the

- furnace is heated to the proper temperature for combustion of the fuel-dust by means of a grate-fire, after which the shaft L is set in motion. Air is now drawn in at the intake 5 of the heating-coil and circulated through the latter, whence it passes through the fan and into the combustion-chamber. The rapid current causes a suction at the pipe J and the fuel drops under force thereof and under 10 the action of gravity into the pipe E³, where it is caught up by the air-current and borne rapidly along into the blower, where it is thoroughly mixed with the air. New material is dumped into the pipe J by the action 15 of the screw conveyer, and the air and fuel supply may be increased as desired by a change in speed of the drive-shaft L, as above stated.
- It is believed that an air-blast supplied in 20 the manner described is greatly to be preferred to any other fluid blast or to any blast supplied in any other manner. Nevertheless, for the purpose of certain claims I do not limit myself to the particular blast shown.
- 25 An important advantage of my construction is that the fuel-box may be located in any part of the boiler-room or in any available space adjacent thereto. The discharge-points of the fuel-box may be below the level 30 of the fire-box without injuriously affecting the working for the reason that the screw

conveyers work in a horizontal plane and the fuel is raised or carried any desired distance within reasonable limits by the suction action of the blower.

35

The combined features of a heated-air supply and the thorough commingling of the same with the fuel-dust attained by my construction are of the highest importance in insuring a "clean fire," without which a furnace cannot be successfully operated with fuel of this nature.

40

What I claim as new, and desire to secure by Letters Patent, is—

In a furnace for burning finely-divided fuel, 45 the combination with the combustion-chamber, or chambers, of a fuel-box provided with downwardly and outwardly diverging sides and an inverted-V-shaped ridge set into the bottom affording channels on either side of 50 the V, a shaker G' slidingly surmounting said ridge, ducts leading from said channels near one end to the combustion-chamber, screw conveyers in said channels, air-pipes communicating with said ducts, and a fluid blast 55 connected with the system, substantially as and for the purpose set forth.

JOHN FLAHERTY.

In presence of—

R. T. SPENCER,
D. W. LEE.
